UNITED STATES PATENT OFFICE

CARL DOLL, OF KOBLENZ, GERMANY, ASSIGNOR TO FRIEDRICH MAUTHE G. M. B. H., UHRENFABRIKEN, OF SCHWENNINGEN, GERMANY

STRIKING CLOCK WITH ELECTRIC WINDING MECHANISM AND RUNNING RESERVE

Application filed February 15, 1929, Serial No. 340,235, and in Germany February 24, 1928.

This invention relates to a striking clock with electric winding mechanism and running reserve.

The novelty consists in that the movement 5 is coupled with the core of the main spring, common for the movement and for the striking mechanism, by a differential gear, which by stopping the arbor connected to the pinion transmits to the movement the driving 10 energy of the spring and effects by rotating the arbor with the pinion the winding of the spring. The novelty consists further in that on a threaded extension of the spring core having a longitudinal bore a disc is rotating 15 as travelling nut, said disc being driven by the running down of the movement and striking mechanism together or separately by each of the two in the same direction, while at the winding it is returned again. At an angle to 20 the axis of the spring core a shaft is mounted with which an anchor is rigidly connected. A disc-shaped travelling nut acts upon said anchor so that at the to and fro movement of the travelling nut an oscillation up to 90° 25 is imparted to an arm connected with the shaft whereby contacts are closed or opened.

In comparison with commonly used constructions the advantage is obtained, that the commonly used weight may be omitted. The 30 clock need further not be adjusted to the accurately perpendicular position, and the construction is considerably simplified as only one spring and one spring barrel are required for operating both mechanisms. Sufficient 35 energy remains to serve as running reserve in case the current should fail.

The gear train can be made in the simplest possible manner without bevel wheels.

An embodiment of the invention is illustrated by way of example in the accompanying drawings in which

Fig. 1 is a front elevation,
Fig. 2 a side elevation and

Fig. 3 a section on line III—III of Fig. 2.
Fig. 4 shows the arbor.

Fig. 5 shows in side elevation several elements put together.

Fig. 6 is a front elevation of the clock work put together and

Fig. 7 is a side elevation of Fig. 6.

The arbor *a* carries a pinion *b* meshing with planet wheels *c* and *d*. The wheels *c* and *d* mesh further with the inner teeth *e* of a wheel *g*. The two planet wheels *c* and *d* are rotatably mounted on studs *r* as shown in Fig. 53 1, said studs being fixed on a disc *f*. Heads *i* of the studs *r* secure the planet wheels *c* and *d* in their position and prevent slipping of the same. The wheel *g* with the inner teeth *e* is partly constructed as a hollow body and 58 mounted on the arbor *a* so that the pinion *b* is accommodated in the hollow space of wheel *g* in which also the planet wheels *c*, *d* and the disc *f* are accommodated.

On the arbor *a* a spring core *h* is further 63 rotatably mounted, on which a spring barrel *v* with spring *j* is secured. The disc *f* is screwed on the spring core *h*. The spring barrel *v* has a tooth rim *v'* and drives the wheels *x*, *y*, *z* of the striking mechanism, 70 while the outer teeth of wheel *g* serve to drive the movement *x'*, *y'*.

The arbor is mounted in plates *k*, *l*, one end of the arbor being extended and projects from the plate *l*, this extension being designed to 75 receive the driving wheel driven from the motor (Fig. 7).

The spring core *h* is threaded on the portion extending from the spring barrel *v*. A nut *t* is screwed on this threaded portion so 80 that it can be moved to and fro. Guide pins *w* fixed on the bottom plate of the spring barrel *v* extend through corresponding holes in disc *t*.

On the plate *h* bearings *m*, *n* are arranged 85 in which a shaft *o* is journalled which cooperates with an anchor *p*, the shaft *o* has on one end an arm *q* designed to act as switch-lever.

The shaft *o* is preferably arranged at right 90 angles to the arbor *a* of the spring core.

The operation is as follows:

When the arbor *a* with pinion *b* rotates, the planet wheels *c* and *d* are also rotated. As 95 the wheel *g* is secured in its position by the movement of the clock, the wheels *c* and *d* roll along the inner teeth *e* of wheel *g*, whereby the spring core *h* is rotated and the spring *j* wound. The counter pressure of the planet wheels *c* and *d* acts at the same time upon the 100

wheel *g* and drives forward the movement. After the winding is finished, the arbor *a* is locked against backward rotation by a ratchet mechanism, in a manner known per se. The 5 planet wheels *c* and *d* roll then on the pinion *b* under the pressure of the pull spring *j* and keep the clockwork running, as they rotate the wheel *g* through the inner teeth *e* of the same. As the outer end of the pull spring is 10 hooked into the spring barrel, the necessary energy is also supplied to the striking mechanism.

At the striking of the clock the spring barrel rotates, whereby the nut *t* is screwed for 15 instance in right hand direction. At the running down of the clockwork the spring core rotates in opposite direction but screws the nut *t* in the same direction in which it is screwed by the spring barrel at the striking. 20 The travel of nut *t* is proportional to the unwinding of the spring. The sum of the rotations of the spring barrel and of the spring core is therefore also proportional to the total unwinding of the spring, immaterial at 25 which end of the spring the unwinding takes place.

The nut *t*, when being shifted, strikes 30 against the anchor *p* and oscillates the same and through it shaft *o* and the switch lever *q* so that the contact is closed in the usual manner. At the renewed winding of the spring effected from the motor, the nut *t* is screwed back until it strikes against the other arm of 35 the anchor *p* so that, by renewed part rotation of shaft *o* and oscillation of the switch lever *q*, the circuit is interrupted.

The shaft *o* is arranged so that at the closing of the circuit the pull spring has unwound only partly in order that, at an accidental 40 cutting of the circuit, the remainder of the spring power in combination with the distance along which the nut *t* has still to travel serves as running reserve.

I claim:—

45 1. In a clock of the character described, the combination of a winding arbor, two driving wheels one for the clock movement and the other for the striking mechanism mounted rotatably on said arbor, a spring 50 barrel connected to one of said driving wheels, a sleeve mounted rotatably on the arbor, a driving spring having one end connected to the barrel and the other to said sleeve, a disc on said sleeve, two gear wheels 55 mounted rotatably on said disc and meshing with an internally toothed rim on the second driving wheel, and a pinion secured to the winding arbor and meshing with said gear wheels.

60 2. A structure as claimed in claim 1 where- 65 in the sleeve has a screw-threaded portion, a nut mounted on said portion, pins on the spring barrel engaging said nut so as to pre- 70 vent relative rotary displacement of nut and barrel, and an electric switch arm arranged 75

so as to be operated by said nut on the latter being axially displaced on the sleeve.

3. A structure as claimed in claim 1 where- 75 in the sleeve has a screw-threaded portion, a nut mounted on said portion, pins on the 80 spring barrel engaging said nut so as to pre- 85 vent relative rotary displacement of nut and barrel, a shaft arranged at right angles to the sleeve, an anchor on said shaft arranged so as to be engaged by said nut for rocking the 90 shaft on the nut being axially displaced on the sleeve and an electric switch arm secured to said shaft.

In testimony whereof I affix my signature.

CARL DOLL.
